PRESSING MACHINE AND ELEMENT

George W. Johnson, Cincinnati, Ohio, assignor
to The American Laundry Machinery Company,
Norwood, Ohio, a corporation of Ohio

Application January 11, 1935, Serial No. 1,300

22 Claims. (Cl. 38—25)

This invention relates to a pressing machine and more particularly to the type used in laundry and garment work.

My present invention provides a pressing machine having a pair of cooperating pressing members, one of said members having a fixed portion which is useful for certain pressing operations and a movable portion which may or may not be used for any given pressing operation. I therefore provide this movable portion of one of the pressing members with means, preferably power operated, for moving the same toward and from the coacting pressing member when desired.

Another feature of my invention is the provision of means for moving the pressing members into coacting relation and means for thereafter moving the above described movable portion of one of said members into ironing engagement with its coacting member. My invention includes means actuated automatically by the press closing means for causing this optional engagement between the movable portion of one pressing member and the coacting portion of the other pressing member.

Another feature of my invention is the provision in an automatically acting press of the type just described, of a device under the control of the operator which when operated completes the train of mechanism by which the movable portion of one of the pressing members is moved into ironing engagement.

My invention also comprises suitable control manuals for presses of the type described including safety two-hand manuals for actuating the press closing power means and a third manual for moving the before mentioned device into operative position to complete the automatic chain by which the press closing means actuates the bed moving means.

My invention also comprises certain novel constructions for pressing elements, including a pressing member having a fixed portion and a portion adjacent thereto movable into pressing position by a flexible and distensible fluid-tight cover member.

Another form of my device includes a pressing member having a fixed pressing portion and a side pressing portion hinged thereto, together with power means for moving the side portion about its hinge into pressing position.

Further features of my invention comprise novel combinations of spring padding with the pressing elements above described and novel arrangements of the cover cloth for this type of pressing member so that the same may be held

taut in various positions of the movable portion of the pressing member.

In the drawings, Fig. 1 is an end elevation, partly in section, of a pressing machine embodying my invention with the pressing members in open position and with the control mechanism shown in diagrammatic form; Fig. 2 is a sectional view of the pressing members of Fig. 1, showing the members in closed position for a pressing operation on the fixed portion of the bed only; Fig. 3 is a sectional view similar to Fig. 2 showing the entire bed in pressing engagement with the coacting head; Fig. 4 is a modified form of bed construction; while Fig. 5 shows still another modification.

In the machine illustrated, on an upstanding bracket of frame 10 is pivotally mounted a head lever 11 carrying a pressing head 12 which may be heated in any well known manner. For operating the head lever to move the head from open to closed position I have provided toggle links 13 and 14 pivotally connected together at 15 and having the upper end of one link pivotally connected to the head lever at 16 and the lower end of the other link pivotally connected to the frame at 17. I have shown power means for moving the links to straightened position comprising a motor 18 having a cylinder 19 in which reciprocates a piston 20 whose piston rod 21 is connected to the toggle knuckle. The motor is suitably mounted on a trunnion 22. A spring 23 connected between toggle link 14 and the frame biases the toggles toward broken position.

The supply of motive fluid for operating motor 18 is by way of a combined flow and exhaust conduit 24 communicating between the cylinder 19 and valve casing 25, which in turn communicates by conduits 26 and 27 with valve casing 28. This latter casing in turn communicates by conduit 29 with a source of motive fluid 30. Valve casings 25 and 28 each contain a normally closed inlet valve 25a, 28a and a normally open exhaust valve 25b, 28b mounted on common stems 25c, 28c for actuation by manuals 25d, 28d, respectively. It will thus be seen that actuation of both manuals 25d and 28d is necessary to supply fluid to motor 18 and upon completion of a power stroke of the latter the piston uncovers a port 31 in the cylinder wall which admits fluid from the motor to conduit 32 which communicates with holding means 33 and 34, each of which comprises a piston 33a, 34a which, by means of a rod 33b, 34b engages an arm 33c, 34c on the respective manuals for holding the same in operated position.

One of the pressing members, in the present instance the bed, has a fixed portion 35 which in the present instance is the central portion of the pressing member but need not necessarily be so arranged. The bed member also has other portions which may or may not be used for a given pressing operation. In the form shown in Figs. 1 to 3 and in Fig. 5, these movable portions comprise a flexible and distensible and substantially fluid-tight cover member 36 which is secured by fluid-tight connections to the fixed portion 35 or other suitable base member so as to provide a means for raising and lowering the side portions of the bed member depending upon whether the latter are to be used in a given pressing operation or not.

In Fig. 4, I have shown a modified form of pressing bed which has a fixed portion 37 which is rigid with the base member 38 and side portions 39 are connected by hinge pins 40 to the fixed pressing portion. Power means is provided for moving the side portions about their hinge pins into and out of pressing engagement with the head. In the form shown, each movable portion 25 is provided with a cylinder and piston motor 41 having a piston rod 42 operatively connected as at 43 with the movable bed portion 39 to swing the latter about its hinge.

Whichever form of bed be used, the supply of motive fluid for actuating the same is by way of a combined flow and exhaust conduit 44 in which is a valve casing 45 housing a normally closed inlet valve 45a and a normally open exhaust valve 45b mounted for simultaneous actuation on a common valve stem 45c. Conduit 44 communicates beyond casing 45 with a supply of motive fluid which may be the source 30 or other suitable supply.

Means under the control of the operator is provided for determining when the press is closed whether the fixed portion only of the bed shall be used for a pressing operation or the entire bed. If the latter is the desired operation, the operator must move a separate manual to cause movement 45 of the movable portion of the bed into pressing position. In the embodiment illustrated, means is provided for actuating the control valves 45a and 45b, for the movable portions of the bed, automatically by a portion of the mechanism which 50 moves the head into closed position. As shown, toggle link 44 is provided with a lug 46 which, when the toggles are moved to straightened position as shown in the dot-dash lines of Fig. 1, lies opposite the valve stem 45c. A device is provided 55 which when operated completes the train of mechanism between lug 46 and valve stem 45c whereby the latter may be operated. This device comprises an abutment member 47 which is movable by means of a servo motor 48 into position 60 between lug 46 and valve stem 45c. The member 47 is normally maintained in inoperative position by a spring 49. The servo motor is suitably constructed to move the member 47 into its operated position and to hold it there while the lug 46 is 65 acting through 47 to operate valve stem 45c. The member 47 has a small projection 50 adapted to overlie the lug 46 when in operated position so as to prevent retrograde movement of the member 47 so long as the links remain in their 70 straightened position. Motive fluid is supplied to servo motor 48 by conduit 51 which communicates with valve casing 52 in which is an open leak port 53 whereby the servo motor is normally exhausted. Casing 52 houses a normally closed 75 inlet valve 52a on a stem 52c for actuation by

manual 52d. An arm 54 rigidly mounted on stem 52c is adapted to overlie a collar 55 on stem 25c so that actuation of manual 25d operates valves 25a and 25b only, but actuation of manual 52d operates the two valves just mentioned and the 5 additional valve 52a.

In Figs. 1 to 3, I have shown spring padding 56 extending across both the fixed and movable portions of the bed which provides a continuous pressing surface over all portions thereof. Over 10 the spring padding is other web material 57 which is a cover cloth or the like and which is held taut by springs 58 held in tension between the edges of the cover cloth and a fixed portion 15 of the frame. It results from this construction that the cover cloth is held taut in all positions of the distensible cover members 36, thus avoiding wrinkles in the cover cloth. The spring padding 20 between the cover member 36 and the heated head or chest member 12 provides an insulating layer 25 between these two so that the cover member is somewhat protected from the heat of the chest. This is very valuable as the cover member is usually of rubber or of impregnated fabric in which the impregnating material is such as to be 25 deteriorated by heat.

The spring padding and cover cloth in Fig. 4 are in all respects analogous to those just described as both of them extend over the entire 30 surface of the bed and the cloth is held taut as before.

In Fig. 5, the fixed portion 35c of the bed is provided with spring padding 59 and the side pressing portions are movable upon distension of the cover members 36 into pressing position so that they form substantially a continuation of the pressing surface of the spring padding 59. In Fig. 5 brackets 60 are provided for supporting the cover members in their deflated positions.

For a pressing operation between the fixed portion of the bed and the coacting portion of the head with the parts in the position of Fig. 1, the operator arranges the lay of the work upon the bed and actuates manuals 25d and 28d. Motive fluid flows through conduits 30 and 29, valve casing 28, conduits 27 and 26, valve casing 25 and conduit 24 to cylinder 19, thus causing a power stroke of piston 20 which moves the toggle links to their straightened position as shown in dot-dash lines in Fig. 1, which causes ironing engagement between the head and the central portion of the bed. Upon completion of the power stroke of piston 20, fluid travels through port 31 and conduit 32 to the holding means 33 and 34 which maintains the valves in their operated positions. To open the press, the operator moves one or both of manuals 25d and 28d against the action of the holding means which opens an exhaust port for motor 18, whereupon spring 23 becomes effective 60 to open the press.

For an ironing operation requiring the entire surface of the bed, the operation is the same as the above except that manuals 52d and 28d are actuated. Manual 52d through arm 54 actuates the valves in casing 25 as previously described to cause operation of motor 18. At the same time, through conduit 27, valve casing 52 and conduit 51, motive fluid is admitted to servo motor 48 which makes a power stroke placing the abutment member 47 in position adjacent 65 valve stem 45c where it is engaged by lug 46 as the toggle links straighten. This operates the valves in casing 45 to admit motive fluid through conduit 44 to the movable portions of the bed, whether these be the inflatable cover members 36 70 75

or the fluid actuated motors 41. In either case, these movable portions are pressed into ironing engagement with the coacting portions of the head. The press is opened as before by movement of manuals 25d and 28d to fluid exhaust position, whereupon the press opens. It will be noted that when the press completely closed and the operator released manuals 52d and 28d, the former returned to its unoperated position but the latter was held by the holding means 34. Servo motor 48 was immediately exhausted through the leak port 53 but the member 47 was held in operative position by the projection 50. When the press is opened, as the toggles move out of straightened position, the member 47 drops and the valves in casing 45 return to the position of Fig. 1 which cuts off the supply of motive fluid to the operating means for the movable portions of the bed.

20 What I claim is:

1. In a pressing machine, a pair of coacting relatively movable pressing members, the first of which has a fixed portion and a movable portion, continuous cover means extending over both of said portions, the second of said members being adapted to coact with both of said portions and being movable into contact with said fixed portion and into spaced relationship to the movable portion of said first member, means for so positioning said second member, and power means for moving the movable portion of said first member into pressure engagement with the coacting portion of the second member.

2. In a pressing machine, a pair of coacting relatively movable pressing members, the first of which has a fixed portion and a movable portion, continuous cover means extending over both of said portions, the second of said members being adapted to coact with both of said portions and being movable into contact with said fixed portion and into spaced relationship to the movable portion of said first member, means for so positioning said second member, and fluid actuated power means for moving the movable portion of said first member into pressure engagement with the coacting portion of the second member.

3. In a pressing machine, a pair of coacting relatively movable pressing members, the first of which has a fixed portion and a movable portion, the second of said members being adapted to coact with both of said portions and having a portion movable to contact said fixed portion of the first member and having another portion movable to a position adjacent the movable portion of said first member, means for so positioning said second member, means for moving the movable portion of said first member into pressure engagement with the coacting portion of the second member, and means controlled by the operator for enabling said first-named means to cause actuation of said second-named means.

4. In a pressing machine, a pair of coacting relatively movable pressing members, the first of which has a fixed portion and a movable portion, the second of said members being adapted to coact with both of said portions and being movable into contact with said fixed portion and into spaced relationship to the movable portion of said first member, means for so positioning said second member, means for moving the movable portion of said first member into pressure engagement with the coacting portion of the second member, whereby to cause pressing action between said second member and the fixed por-

tion of said first member, a manual having a controlling effect on said first named means only, and a second manual having a controlling effect on both of said means, whereby to cause pressing action between said second member and both portions of said first member.

5. In a pressing machine, a pair of coacting relatively movable pressing members, the first of which has a fixed portion and a portion comprising a flexible distensible substantially fluid-tight cover member for moving the pressing face thereof, the second of said pressing members being adapted to coact with both portions of said first member and being movable into contact with said fixed portion and into spaced relationship to said distensible portion of said first member, means for so positioning said second member, and fluid means for distending said cover member.

6. In a pressing machine, a pair of coacting relatively movable pressing members, the first of said members having a fixed portion and a movable portion, a motor for moving said movable portion, control means for said motor, the second of said members being movable into contact with said fixed portion and into spaced relationship to the movable portion of said first member, means for so positioning said second member, and said last-named means having an operative connection for actuating said motor control means.

7. In a pressing machine, a pair of coacting relatively movable pressing members, the first of said members having a fixed portion and a portion hinged thereto, a motor for moving said hinged portion, the second of said members being movable into contact with said fixed portion and into spaced relationship to said hinged portion, means for so positioning said second member, and means for actuating said motor to move said hinged portion into engagement with the coacting portion of said second member.

8. A pressing element comprising a fixed portion, a portion having an edge hingedly connected with said fixed portion, and motor means for moving said hinged portion about its hinged connection.

9. A pressing element comprising a fixed portion, spring padding thereon, a portion comprising a flexible distensible substantially fluid-tight cover member, and fluid means for distending said cover member to move the portion of the pressing surface overlying said cover member into position to form substantially a continuation of said spring padding.

10. A pressing element comprising a fixed portion, spring padding thereon, and a portion comprising a flexible distensible substantially fluid-tight cover member.

11. A pressing element comprising a fixed portion, a portion comprising a flexible distensible substantially fluid-tight cover member, fluid means for distending said cover member, and spring padding overlying both of said portions.

12. A pressing element comprising a fixed portion, a portion comprising a flexible distensible substantially fluid-tight cover member, fluid means for distending said cover member, spring padding overlying both of said portions, a cover cloth over said spring padding, and means for holding said cloth taut under varying degrees of cover member distension.

13. A pressing element comprising a fixed portion and a movable portion adapted to form part of one continuous pressing surface, said mov-

- able portion being movable toward and from the general plane of said pressing surface, a continuous cover member extending over both of said portions, and means for holding said cover member taut.
- 5 14. A pressing element including a flexible distensible substantially fluid-tight cover member for lifting the pressing surface of said element, means for distending said cover member, a cover cloth or the like extending across the surface of said element, and means at the edges of said cloth for holding the same taut under varying degrees of cover member distension.
- 15 15. A pressing element adapted to coact with a heated ironing surface and including a flexible distensible substantially fluid-tight cover member for lifting the pressing surface of said element into engagement with said heated surface, means for distending said cover member, and a 10 layer of material having a heat insulating effect interposed between said cover member and said heated surface.
- 20 16. A pressing element comprising a fixed pressing portion and a side pressing portion comprising a flexible distensible substantially fluid-tight cover member secured in position adjacent said fixed portion, said side portion being adapted when said cover member is distended to form a 25 continuation of said central portion.
- 30 17. In a pressing machine, a first pressing member, a second coacting pressing member movable toward and from coacting position adjacent said first member, power actuated means for moving the pressing surface of said first member toward the second member in said coacting position, a control member therefor, power means including motion transmitting mechanism for moving said second member to said coacting 35 position, means for actuating said control member by a portion of said mechanism when said second member moves into coacting position, said last-named means including a device adapted when operated to form an operative connection between said mechanism and said control member, and two-hand control means for said power means including a manual adapted to operate 40 said device.
- 45 18. In a pressing machine, a frame, a head lever pivotally mounted on the frame, a pressing head on said lever and movable thereby from open to closed position, toggle links connected between said frame and head lever for moving the latter, a fluid motor for moving said toggles to straightened position, fluid supply means for 50 said motor including two spaced manuals, a pressing bed on said frame, said bed having a fixed portion adapted to contact said head in its closed position, said bed having a portion adapted to lie adjacent said head in closed position and movable theretoward, fluid actuated 55 means for moving said movable portion of said bed, fluid supply means for said last-named means including a normally closed inlet valve positioned adjacent said toggle links in their straightened position, a device adapted when operated to form an operative connection between one of said links and said valve for opening the latter when said toggle links are straightened, a servo-motor for operating said device, and fluid supply means for said servo-motor includ-
- 60 ing a manual having an operative connection with one of said first-named manuals.
- 65 19. In a pressing machine, a pair of coacting relatively movable pressing members, the first of which has a fixed portion and a movable portion, the second of said members being adapted to coact with both of said portions and being movable into contact with said fixed portion and into spaced relationship to the movable portion of said first member, power means for so positioning said second member, power means for causing movement of the movable portion of said first member into pressure engagement with the coacting portion of the second member, a control member for said second-named power means, 10 and means for actuating said control member by operation of said first named power means.
- 15 20. In a pressing machine of the class described, head and bed pressing members having coacting pressing portions relatively movable toward each other in two steps, a first step into adjacent position and a second step into final pressure engagement, power means for causing said relative movement between said pressing portions, power supply for said power means, 20 control means for said supply including a control member for causing said first step movement, a control device for energizing said power means to cause said second step movement, means for actuating said control device including an enabling device and means acting therethrough by first-step operation of said power means, said enabling device being normally in disabling position, power means for moving said enabling device to enabling position, and a control member 25 for said last named power means spaced from said first named control member to require two hands of an operator for conjoint operation of both control members.
- 30 21. In a pressing machine of the class described, head and bed pressing members having coacting pressing portions relatively movable toward each other in two steps, a first step into adjacent position and a second step into final pressure engagement, fluid actuated power means for causing said relative movement between said pressing portions, a fluid supply for said means, control means for said supply including two control valves both of which must be actuated conjointly for causing first-step operation of said power means, control valve means for causing second-step operation of said power means, means for actuating said valve means including an enabling device and means acting therewith and controlled by first-step operation of said power means, said enabling device being normally in disabling position, a servo-motor adapted when supplied with motive fluid to move said enabling device to enabling position, a pair of 40 manuals spaced to require two hands of an operator for conjoint operation thereof, said manuals being arranged to actuate said two control valves, and fluid supply means for said servo-motor controlled by at least one of said manuals.
- 45 22. A pressing element having a pressing surface comprising a fixed portion and a portion including a flexible distensible substantially fluid-tight cover member arranged so that a pressing operation may be performed substantially simultaneously upon both portions of said surface.
- 50 70 GEORGE W. JOHNSON.

CERTIFICATE OF CORRECTION.

Patent No. 2,079,291.

May 4, 1937.

GEORGE W. JOHNSON.

It is hereby certified that error appears in the printed specification of the above numbered patent requiring correction as follows: Page 3, first and second columns, lines 74-75 and 1, claim 4, strike out the words and comma "whereby to cause pressing action between said second member and the fixed portion of said first member," and insert the same after "only," in second column, line 3, same claim; page 3, second column, line 1, claim 4, before "a manual" insert the words control means for both of said means including; and that the said Letters Patent should be read with these corrections therein that the same may conform to the record of the case in the Patent Office.

Signed and sealed this 13th day of July, A. D. 1937.

Henry Van Arsdale

(Seal)

Acting Commissioner of Patents.
